UNITED STATES PATENT OFFICE

FREDERICK A. STOREY, OF ENDICOTT, NEW YORK, ASSIGNOR TO THE TABULATING MACHINE COMPANY, OF ENDICOTT, NEW YORK, A CORPORATION OF NEW JERSEY

CONTROL DEVICE FOR TABULATING MACHINES AND THE LIKE

Application filed October 22, 1925. Serial No. 64,092.

This invention covers improvements in record-controlled tabulating machines, and has for its principal object the provision of devices which will automatically stop the 5 operation of the machine when a predetermined number of entries have been made on the record sheet.

Another object is to provide means for printing a total one or more times without 10 clearing the accumulator.

In certain classes of work done by tabulating machines the records are printed on comparatively short record sheets, and sometimes totals are carried from one sheet to the next.

15 The devices disclosed in my present invention include manually settable means causing the machine to stop when a predetermined number of printing operations have occurred. This obviates the necessity of the operator 20 watching the machine to prevent overrunning the end of the sheet.

After a sheet or page has been filled a total may be printed at the bottom of the sheet and that same total printed again at the head 25 of the next sheet, thus carrying along the total until all entries are finished on a plurality of sheets.

In the drawings,

Fig. 1 is a front view of the complete machine with my present invention attached.

Fig. 2 is a sectional view of card feeding and brush devices.

Fig. 3 is a view of the dial of my device.

Fig. 4 is a vertical cross section of my invention.

Fig. 5 shows details of a portion of the mechanism in Fig. 4 in a different position.

Fig. 6 is a section on line 6—6 of Fig. 4.

Fig. 7 is a sectional view of a portion of 40 the tabulator reset mechanism with my invention attached.

Fig. 8 is a detail showing interconnection between the tabulator mechanism and the present invention.

45 Fig. 9 is a circuit diagram of the tabulator with my invention incorporated therein.

Reference will now be had to Fig. 1 which shows the general arrangement of a printing tabulating machine with my present invention attached. The tabulating machine it-

self is fully described in the copending application of Clair D. Lake, Serial No. 639,153, filed May 15, 1923. It comprises a card feeding and analyzing section 20, a counter or accumulator section of five accumulators 55 designated generally at 22, and at the right a printing section 24. Below the counters is the control section 26. The section embodying my invention is shown at 28. The reset shaft 30 extends across the machine in front 60 of the counters and at each counter there is a "zero button" 32 which controls the total-taking and reset operations of that particular counter.

The machine is driven by tabulating motor 65 TM through belt 34 and pulley 36 on the machine. In connection with pulley 36 the usual tabulating clutch is provided of the type indicated at 38 in Fig. 2. The clutch is controlled by magnet 40 through latch lever 42 70 and is adapted to couple the motor TM with the card feeding section of the machine.

Cards are fed downwardly one at a time from magazine 42 by picker device 44 into the control of successive pairs of feed rolls 75 46 that carry the cards past the upper control brushes 48 and the lower analyzing brushes 50 after which the cards are deposited on the discharge stack 52.

Fig. 7 shows the reset motor RM and details of the reset and paper feed devices contained within section 54 of the machine and the relationship of the present invention thereto.

As is fully explained in the above copending application, when a total-taking and reset operation is to be carried out, motor RM is started and reset magnet 56 energized. The energization of magnet 56, through the instrumentality of clutch device 58 actuated by magnet-controlled arm 60, turns shaft 62 one revolution. Shaft 62 carries a total-taking cam 64 and a gear 66 which has teeth in only half its circumference. During the first half of the revolution of shaft 62, cam 64 through arm 68 actuates the printing mechanism to print the total standing on the accumulators at that time. During the second half revolution of shaft 62 the toothed portion of gear 66 rotates gear 70 and reset 80 95 100 magnet 56 de-energized.

shaft 30 one revolution. This results in the resetting of all accumulators which have their zero buttons 32 in latched position. Those accumulators having zero buttons unlatched retain the amounts then standing on them.

Push rod 69 is provided to raise arm 60 thereby actuating clutch 58 and closing contact 71 to bring about a manually initiated 10 total-taking and reset operation when desired.

The devices designated generally as 72 are rocked in connection with all printing operations to actuate the paper feed by means of 15 vertical link 74.

For the purposes of my present invention I attach to device 72 an upstanding arm 76 which is rocked with 72 whenever a paper feeding operation occurs. Pivoted at 20 attached to the upper end of 76 is one end of a substantially horizontal link 78, the other end being pivotally attached to rocking member 80 (Fig. 8) of my invention which will now be described.

25 Member 80 is freely mounted on shaft 82 (Figs. 4, 5 and 6) on which is fast the disc 84 on the rim of which are cut the equally spaced teeth 86. Corresponding to each tooth 86 and adjacent thereto is a hole 88 30 drilled in disc 84.

Freely mounted on shaft 82 and extending horizontally therefrom is arm 90. The outer end of arm 90 has formed on it a horizontal lip 92 from which extends downwardly the contact controlling non-conducting stud 94. Arm 90 is also provided with cam surfaces 96 and 98 and stop lug 100, all for purposes to be later explained. Spring 99 holds arm 90 normally in raised position 35 against pin 101. Carried on the upper portion of the free end of arm 80 is the ratchet pawl 102, pivoted at 104, and normally held in engagement with a notch on disc 84 by spring 106. On the back of dog 102 is pin 40 108 arranged for engagement by surface 96 at the proper time. Mounted on the frame is a retaining pawl 110 drawn into engagement with teeth 86 by spring 112. On pawl 45 110 is a pin 114 arranged for engagement by surface 98 at the proper time in the cycle 50 of operation. Spiral spring 116 serves to draw disc 84, when free, to home position with its lug 118 against stop 120.

On the front of the device is a settable dial 55 122 (Figs. 3 and 6) having a graduated scale 124 corresponding with holes 88 and cooperating with a fixed index 126. Set into the dial at zero position is a plunger 128 pressed inwardly by spring 130 bearing 60 against collar 132 on the plunger. Collar 132 also serves to limit the inward travel of the plunger. The outer end of the plunger is provided with knob 134 for the convenience of the operator. In normal position 65 plunger 128 is always in a hole 88 in disc 84.

Pivoted to the frame at 136 is a bell crank lever having an upwardly extending latch 138 and a horizontal arm 140. This lever is urged clockwise by spring 142. Vertical arm 138 has a notch 144 which engages lip 70 92 when the lip is lowered and thereby holds arm 90 in depressed position. Horizontal arm 140 has a non-conductor pad 146 which controls contact 150.

In operation, if the operator wants the 75 machine to stop when the paper feed has been actuated any particular number of times, say 14, he withdraws plunger 128 from engagement with disc 84 by means of knob 134, then turns dial 122 until the 14 80 graduation is at index 126 and lets plunger 128 enter the hole 88 with which it is then aligned (Figs. 3, 4 and 6). The machine is then started and every time a paper feed operation takes place link 78 is reciprocated 85 and member 80 is rocked sufficiently to rotate disc 84 one tooth space by means of dog 102, the disc being restrained against backward motion by retaining pawl 110.

Finally when the fourteenth paper feed 90 has taken place disc 84 has been rotated until its zero graduation is at index 126 and plunger 128 has contacted with lug 100 on arm 90, thereby moving arm 90 to its depressed position (Fig. 5). When arm 90 95 moved downwardly its cam surfaces 96 and 98 acting against pins 108 and 114 respectively, forced dogs 102 immediately, and 110 on its next up stroke, out of engagement with disc 84 which thereupon is drawn back 100 by spring 116 to home position with lug 118 against stop 120 and dial 122 as in Fig. 3.

Arm 90 is retained in depressed position by notch 144 of arm 138 engaging lip 92. In this position contacts 150, 160 and 170 are 105 all open (Fig. 5), whereas in normal position only 150 is open while 160 and 170 are closed (Fig. 4).

If now key 172 be depressed against the pull of its spring 174, pin 176 will depress 110 arm 140 and unlatch arm 138 from lip 92 thereby allowing spring 99 to draw arm 90 to its normal raised position against pin 101, permitting contacts 160 and 170 to close and pawls 102 and 110 to again engage 115 teeth 88. If desired, key 172 may be depressed sufficiently to close contact 150 and restart the machine, as will later be explained.

By depressing key 178, arm 90 may be 120 manually moved by pin 179 to the stop position at any time and ratchet disc 84 allowed to return to home position.

The primary purpose of the mechanism above described is to manipulate electric 125 contacts by which the action of the machine is controlled. A full understanding of how such control is effected may be obtained from the wiring diagram in Fig. 9 which covers diagrammatically the circuits in the

well known type of tabulating machine such as is described in the application above referred to. I shall describe here only such portions of the diagram as are essential to 5 a working knowledge of my present invention.

The lower part of the diagram represents the circuits of the counters or accumulators, the zero button 32 being represented conventionally in the usual manner and the contacts controlled thereby being designated 180. For my present purpose I provide switches 182 by which each zero button contact 180 may be bridged if desired.

15 The middle part of the diagram relates to the usual automatic control devices with which we are not particularly concerned.

In the circuit between stop key 192 and the right side of line I insert contact 170, 20 while in the circuit with automatic start key 186 and stop key 188 I insert contact 160. Contact 150 is placed in a circuit to bridge start key 190.

When the parts are brought to the position 25 shown in Fig. 5 the machine stops because contact 170 opens which has the same effect as if the usual stop key 192 were depressed. Also, while in that position a total-taking and 30 reset operation cannot be initiated automatically through automatic reset switch 194, because the switch is in circuit with the open contact 170. Neither can the machine automatically restart because open contact 160 breaks the circuit through automatic start 35 switch 186.

If under these conditions it is desired to take a total and reset, reset key 196 is depressed or push rod 69 is raised. If rod 69 be raised, contact 71 is closed and a circuit is established 40 through motor RM, magnet 56 and contact 71 to right side of line, whereas if key 196 be depressed the circuit is established through contact 198 instead of contact 71. If zero button 32 is in latched position during the 45 above reset cycle, the total is printed and the counter reset to zero in the usual manner. If it is desired to print the total from any counter and not reset it to zero the result is accomplished by leaving zero button 32 unlatched 50 and closing by-pass switch 182. Under these conditions contact 180 will be open but a circuit will be provided through switch 182, therefore, the total will be printed even though zero button 32 and contact 180 are not 55 in the usual total-taking positions. The fact that zero button 32 is unlatched prevents the usual mechanical resetting of the counter, so the machine with the above setting, prints the total without clearing the counter, and will 60 print that total as often as either reset key 196 or rod 69 is actuated, thus permitting the operator to print a total at the bottom of one record sheet and at the top of the next sheet.

After the printing of totals is finished, the 65 machine is restarted by depressing key 172

sufficiently to close contact 150, or by pressing the usual start key 190. At this time arm 90 having been released from latch 138 has returned to normal raised position and contacts 160 and 170 are closed, so the machine is ready 70 to print the next sheet and, as before, stop at a predetermined point on the sheet.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of these may be altered and others omitted and some of the features of each modification may be 80 embodied in the others without interfering with the more general results outlined, and the invention extends to such use.

What I claim is—

1. In a tabulating machine, in combination, an automatic restart circuit, an automatic reset circuit, an intermittently operable paper feed device and means settable to open said restart and reset circuits after a predetermined number of operations of said paper 90 feed device.

2. In a tabulating machine, in combination, an automatic restart circuit, an automatic reset circuit, an intermittently operable paper feed device, means settable to open said restart and reset circuits after a predetermined number of operations of said paper feed device, and manually operable means to 100 initiate restart or reset operations.

3. In a machine of the class described, in combination, an accumulator, total printing mechanism, reset mechanism for said accumulator, paper feed devices, settable means to stop said machine after a predetermined number of operations of paper feed devices, and means thereafter operable to actuate said 105 total printing and reset mechanisms.

4. In a machine of the class described, in combination, an accumulator, total printing mechanism, reset mechanism for said accumulator, paper feed devices, settable means to stop said machine after a predetermined number of operations of said paper feed devices, and means thereafter operable to actuate said total printing mechanism and suppress the actuation of said reset mechanism.

5. In combination, in a machine operated by a motor, a member for controlling the operation of the motor, a settable device automatically actuatable a predetermined amount from a zero position to thereafter operate the said member to stop said motor, and means independent of the settable device for actuating said member to stop the motor, said 125 130

means automatically resetting said device to its zero position.

6. In combination, in a machine operated by an electric motor, normally closed contacts for controlling the motor operation, a device automatically actuatable a predetermined amount from a zero position to effect opening of said contacts, and means for latching the contacts in open position.

10 7. The invention as set forth in claim 6, and manual means for releasing the latching means.

8. In combination, in a machine operated by an electric motor, start contacts normally open and adapted to be momentarily closed to start the motor, control contacts normally closed to stop the motor, a device automatically actuatable a predetermined amount from an index position to effect opening of 20 the normally closed contacts and thereby stop the motor, means for latching the latter contacts in open position, and means for closing the normally open contacts to start the motor, said latter means simultaneously actuating 25 said latching means in a direction to release the normally closed contacts.

9. In combination in a tabulating machine, an automatic restart circuit, and control contacts therein, an automatic reset circuit and 30 control contacts therein, a member having connections to each of said control contacts to operate them simultaneously, and means automatically actuatable from a zero position to a predetermined and settable position 35 for operating said member.

10. The invention as defined in claim 8, and means for latching said member after an operation thereof.

11. The invention as defined in claim 8, 40 means for latching said member after an operation thereof, start contacts and manual means for operating said start contacts and releasing said latching means from said member.

12. In combination, in a tabulating machine, a control circuit containing control contacts, a member for operating said contacts, a device automatically actuatable from an index position to a predetermined and adjustable position for operating said member, 50 and a key adapted to be manually operated to actuate said member independently of the device.

In testimony whereof I hereto affix my 55 signature.

FREDERICK A. STOREY.
